POLE MOUNTING

George B. Spring, Newtonville, Mass., assignor to
The Eastern Malleable Iron Company, New
Britain, Conn., a corporation of Connecticut

Application March 19, 1931, Serial No. 523,786

1 Claim. (Cl. 72—84)

This invention relates to pole mountings for poles carrying transmission lines such for instance as telephone poles, telegraph poles, electric light poles, etc.

5 One of the objects of the invention is to provide an improved pole mounting which is relatively inexpensive to manufacture and which can be easily set in the ground and on which the pole may be firmly supported with the lower end 10 of the pole above the surface of the earth.

Another object of the invention is to provide a pole mounting for this purpose which can be readily made at the factory and transported completely made to the point where it is to be used. One advantage resulting from this is that 15 the improved pole mounting can be installed simply by means of the ordinary tools used in setting a pole.

Another object of the invention is to provide 20 a pole mounting of this character which can be readily set in the earth adjacent a pole which is in use for supporting transmission lines and to which such pole can be readily transferred while in erected position.

25 Other objects of the invention are to provide improvements in pole mountings all as will be more fully hereinafter set forth.

In the drawing:

Fig. 1 is a view illustrating a pole mounting 30 embodying my invention;

Fig. 2 is a similar view illustrating a slightly 35 different way in which the invention may be applied;

Fig. 3 is a view of one of the supporting members with the foot portion broken out leaving the post and reinforcement in elevation;

Fig. 4 is a section on the line 4—4, Fig. 1;

Fig. 5 is a section on the line 5—5, Fig. 3.

In the drawing, 1 indicates the pole which is 40 supported on my improved pole mounting. The pole mounting comprises one or more pole-supporting elements adapted to be set into the ground and on which the pole is supported and to which the pole is firmly clamped.

45 Each pole-supporting member comprises a foot portion 2, preferably of concrete, which is relatively long compared to its cross-sectional area and which preferably has a cross-sectional area somewhat less than the cross-sectional area of 50 the pole 1. In practical use I propose to make these foot portions about five feet long. Each supporting member also comprises a post element 3 of metal which has its lower end 4 embedded in the concrete 2 for a considerable distance 55 and the upper end 5 of which rises from

the upper face 6 of the foot member for a suitable distance.

The inner face 7 of the post 3 is preferably curved to fit the exterior of the pole and said posts are shown as having a general T shape in 60 cross section and provided with a strengthening rib 8 which extends longitudinally thereof on the back face.

In making the supporting member the metal 65 post 3 may be placed in a suitable mold with the upper end projecting and then the mold may be filled with concrete to produce the foot portion 2 and when the concrete has set the supporting member is complete, ready for installation.

If desired, the concrete foot portions may be 70 reinforced with metal. One way of doing this is to provide reinforcing rods 20 which extend longitudinally of the foot portion. In the construction shown there are three such rods, one 75 on either side of the web 8 of the post 3 and the other on the side of the post facing the pole, but the number of reinforcing rods which may be used may be varied without departing from the invention. I have also shown a further reinforcement in the form of a coarse wire mesh 21 which is wrapped around the post 3 and which provides transverse as well as longitudinal reinforcement.

The upper face 6 of each foot is somewhat 80 larger than the cross-sectional dimension of the post 3 and in the completed supporting member the portion 9 of the upper face 6 of the foot forms a step or seat on which the pole 1 may rest. The portion of the web or fin 8 85 which projects above the foot 2 is provided with a plurality of apertures 10 adapted to receive clamping members by which the pole may be clamped to the face 7.

For supporting a relatively small pole a single 90 supporting member may be sufficient as shown in Fig. 2. In installing the supporting member the concrete foot portion 2 is set into the earth at the desired point with the upper surface 6 thereof projecting somewhat above the top surface 12 of the earth. The pole 1 is then placed in position with the lower end resting on the seat portion 9 and the pole is then clamped to the face 7 by suitable clamping devices 11 which may be of the type illustrated in my patents No. 1,679,747, August 7, 1928, No. 1,755,461, April 22, 1930 and No. 1,789,393, January 20, 1931. With this construction the bottom face 13 of the pole is spaced above the surface of the earth and is, therefore, not subjected to the 105 110

decaying action which is the result of the pole being in contact with the earth.

This mounting can be constructed complete at the factory and transported in its complete form to the place where it is to be installed and it may be as readily set into the earth as an ordinary pole so that no special tools are needed for installing the mounting other than such as are commonly used in setting a pole.

10 After the mounting has been set the pole can be easily attached thereto by placing the lower end 13 of the pole on the seat 9 and then applying the clamping members 11 which securely clamp the pole to the posts. The posts should 15 have a sufficient overlapping engagement with the pole to hold the pole firmly.

For mounting large poles I propose to use two of these supporting members as shown in Fig. 1. Each supporting member may be independently set in the earth and arranged so that the lower end of the pole may be placed between them, the pole being supported partially on the seat portion 9 of one supporting member and partially on the seat portion 9 of the other supporting member.

25 After the pole has been put in position the two supporting members are clamped firmly to the pole by means of clamping elements 15 which are connected to the ribs 8 of the posts and which engage the side faces of the pole exposed between the posts.

30 In making the foot portions 2 I preferably will so form them that the inner faces 16 thereof are somewhat pointed in a transverse direction. 35 When the two supporting portions are employed the two pointed or tapered sides 16 face each other as seen in Fig. 4. An advantage of this construction is that the pointed shapes of the foot portions facilitate their being drawn together slightly in order to enable the upper ends of the posts to be firmly clamped to the pole.

35 In installing the pole mounting shown in Fig. 1 the two supporting members will be set in the earth at approximately the correct distance apart to accommodate the pole which is to be set, this distance varying with the size of the pole. After the pole is placed in position with the lower face 13 thereof resting on the two seat portions 9 it may be found that the upper ends 5 of the posts 3 do not fit tightly against the pole. When the clamps 15 are applied the upper ends of the posts will be drawn tightly against the pole and the pointed shape of the faces 16 facilitates any slight movement of the foot portions 2 toward each other necessary to permit the posts to be firmly clamped to the pole. These tapered or pointed surfaces 16 tend to crowd the earth away so as to allow this necessary movement.

40 My improved pole mounting may be used for the mounting of new poles or may be used as

a support for a pole which has been in use and which has become more or less decayed at the surface of the earth. In the latter case the decayed pole will be cut off close to the earth while still in its erected position and the lower end of the pole may then be set slightly to one side. The two supporting portions may then be set in the earth at approximately the proper distance apart to accommodate the pole and with the upper surfaces 6 of the foot portions extending a short distance above the surface of the earth. After the two supporting portions have been set the pole may be placed between the upper ends of the posts 5 with the lower end resting on the seats 9 and the clamps 15 applied to clamp the pole firmly in place.

45 These operations can be carried out without disturbing any of the wires carried by the pole.

If desired, the seats 9 may be formed with drain grooves 17 which allow the water to readily drain off from the seats thus preventing the accumulation of water at this point which might have a tendency to cause decay. It will be noted that the foot portion has a larger cross-sectional area at the upper end than at the lower end.

50 The advantage of this is that the larger upper end gives an increased earth resistance at the surface of the earth where this is most needed. At the lower end of the foot some distance below the surface of the earth the earth will present a greater resistance than at the surface of the earth where it is more easily crowded to one side and by making the upper end of the foot portion larger an increased earth resistance is provided at the surface of the earth where such 105 increase is most needed to prevent the pole from swaying.

55 I claim:

60 A pole mounting comprising two pole-supporting members each having a foot portion of concrete adapted to set into the earth with the upper end of the foot portion projecting slightly above the earth, a metal post having its lower end embedded in each foot portion, the cross-sectional area of each foot portion being somewhat less than the pole to be supported but greater than the posts, the portion of the upper face of each foot inside of the post constituting a pole-supporting seat, a pole situated between the two posts and resting on said seats, and means to clamp the pole to the upper ends of said posts, the adjacent faces of the foot portions being spaced apart with the space between said faces filled with earth, and also being pointed to facilitate the drawing of the foot portions together in the earth as the posts are clamped to the pole said foot portion having a progressively-increasing cross-sectional area from the bottom to the top whereby the larger end presents an increased surface for earth 135 resistance.

65 GEORGE B. SPRING.
